(57) **CLAIM**

The ornamental design for a combined paint cup and brush holder, as shown and described.

DESCRIPTION

FIG. 1 is a top perspective view of a combined paint cup and brush holder showing my new design;

FIG. 2 is a right side elevation view thereof, the left side elevation being a mirror image of this right side view;

FIG. 3 is a front elevation view thereof;

FIG. 4 is a rear side elevation view thereof;

FIG. 5 is a bottom plan view thereof;

FIG. 6 is a top plan view thereof; and,

FIG. 7 is a sectional view taken along the plane designated by the line labeled 7—7 of FIG. 6.
